(57) CLAIM

The ornamental design for a cosmetics container, as shown and described.

DESCRIPTION

FIG. 1 is a perspective view of a cosmetics container showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof, shown in enlarged scale;

FIG. 7 is a bottom plan view thereof, shown in enlarged scale; and,

FIG. 8 is an exploded perspective view thereof.

The dot-dash broken lines of FIG. 8 is included to show relationship of the top to the container only and forms no part of the claimed design.

1 Claim, 8 Drawing Sheets
